UNITED STATES PATENT OFFICE.

LOUIS W. PRUSS, OF MINNEAPOLIS, MINNESOTA.

FLOUR-DRESSING MACHINE.

SPECIFICATION forming part of Letters Patent No. 271,361, dated January 30, 1883.

Application filed August 18, 1882. (No model.)

To all whom it may concern:

Be it known that I, L. W. PRUSS, of Minneapolis, in the county of Hennepin and State of Minnesota, have invented certain Improvements in Flour-Dressing Machines, of which the following is a specification.

This invention relates to that class of flour-dressing or bran-dusting machines wherein a cylindrical or polygonal reel is combined with 10 internal rotary beaters or blades to agitate the material and throw the same outward against the bolting-surface of the reel.

The invention consists in combining with 15 said machine a fan or fans arranged upon the beater-shaft and adapted to produce a draft or current of air through the reel from the tail toward the head. In machines of this type as ordinarily constructed a draft of greater or less strength passes through the reel from the 20 head toward the tail, or in the same direction as that in which the material flows through the machine, the effect of which draft is to carry therewith a considerable percentage of fine flour which passes out of the machine with the 25 tailings, instead of going through the ganze of the dressing-cylinder. This wastage, which it is the object of my invention to overcome, is completely remedied by means of the draft or current of air passing through the reel in the 30 opposite direction from that in which the material is carried.

In applying my invention I prefer ordinarily to make use of rotary fans consisting of metallic sheets provided with radial perforations and oblique blades, and to mount these fans upon the beater-shaft or the hubs thereon. These fans may be constructed in any desired 35 number at suitable points throughout the length of the machine, and they may be secured by collars, set-screws, or other suitable devices to admit of their being readily adjusted, if required.

I am aware that machines have been constructed wherein oblique revolving blades were 45 arranged to travel in close proximity to the surface of the reel for the purpose of acting upon the bran and retarding its motion through the reel. These devices are not to be confounded or associated with the rotary fan employed 50 in my machine, the object and mode of action in the two cases being widely different.

Referring to the accompanying drawings, Figure 1 represents a longitudinal vertical section through the center of a flour-dressing machine provided with my improvements. Fig. 55 2 is a vertical cross-section of the same, various parts of ordinary construction which have no relation to the present improvements being omitted in both figures.

Referring to the drawings, A represents the 60 external case or chest, and B the slightly-inclined reel, mounted lengthwise within the body, usually arranged to revolve therein.

C represents the revolving blades or beaters carried by radial arms *a*, connected by central 65 hubs, *b*, to a central rapidly-revolving shaft, D.

The above parts may be of ordinary or suitable construction and connected with suitable driving mechanism, which will cause the beaters C to revolve rapidly within the reel at a 70 short distance from its inner surface.

E represent the fans constituting the subject-matter of the present invention. The drawings represent six of these fans distributed at uniform distances apart within the 75 reel, being mounted upon the central beater-shaft, D, and inside of the beater arms or blades C. Each fan consists of a circular sheet or disk of metal provided with numerous radial slots or openings, *c*, formed by cutting the 80 metal loose on two sides and bending the same outward obliquely from the face of the disk, so as to form fan-blades *d*, the surfaces of which stand obliquely in relation to the plane of rotation. The outer ends of the fan-blades are 85 preferably connected to the fans of the disk by means of thin metal blades *e*, soldered or otherwise secured thereto, as shown, these plates serving to hold the blades firmly in position, as well as to prevent air from being carried 90 outward radially from the ends of the blades. The fans which are adjacent to the hubs of the beaters may be attached to said hubs, as shown, while those fans which occupy intermediate or 95 central positions will be attached to special hubs or collars secured upon the shaft by set-screws, as shown, or in any other suitable manner.

It will be observed that the fans constructed as above do not approach closely to the bolting-surface, and do not interfere with the motion of the heavy material longitudinally 100

through the machine in contact with the bolting-surface. Inasmuch, however, as the rotary shaft is driven at a high speed, the fans produce a blast or current of air of considerable strength through the machine from the tail to the head of the reel, this blast being sufficient to retard the fine flour until it finds its way through the bolting-surface, without, on the other hand, interfering with the flow of the heavy material. In short, the machine provided with the improvement operates in all respects in the ordinary manner, with the exception that a light draft of air passes through the reel from the tail to the head.

15 As before stated, the fans may be constructed and attached in any suitable manner, provided only that they serve to produce a draft through the machine in the direction indicated without interfering with the ordinary functions of the beaters or the usual passage of the coarse material through the machine.

The present invention is restricted to the application of the fans, as herein set forth, various other details represented in the drawings 20 constituting the subject-matter of another and prior application filed in my name for a patent.

Having thus described my invention, what I claim is—

1. In a flour-dressing or bran-dusting machine, the combination of a reel, internal revolving blades or beaters moving adjacent to the surface of said reel, and central rapidly-revolving fans, as described, to produce a current of air through the reel from the tail toward the head. 30

2. In a flour-dressing-machine, an external bolting or dressing reel, in combination with central rapidly-revolving fans adapted to produce a draft through the machine from the tail to the head, and blades or beaters rotating between the fans and the inner surface of the reel, substantially as shown. 40

3. The combination of the reel or bolting-cylinder and the central rapidly-revolving shaft provided with both the beaters or blades and the fans, substantially as shown. 45

4. In a flour-dressing machine, substantially as described, central fans to produce a draft from the tail toward the head, each fan consisting of a disk or plate provided with numerous openings and oblique blades opposite thereto, substantially as described. 50
